UNITED STATES PATENT OFFICE.

ROBERT WILLIAM SEMPLE, OF BROOKLYN, NEW YORK

COMBINED ARTIST'S PALETTE AND COLOR-DISH.

SPECIFICATION forming part of Letters Patent No. 787,123, dated April 11, 1905.

Application filed January 5, 1905. Serial No. 239,714.

To all whom it may concern:

Be it known that I, ROBERT WILLIAM SEMPLE, a subject of the King of England, residing at 181 Prospect Park west, Brooklyn, in the county of Kings, State of New York, have invented a new and useful Combined Artist's Palette and Color-Dish, of which the following is a specification.

The object of my invention is the production in one integral form of an artist's palette, color-dish, or slab which shall have certain advantages over those commonly used. Its construction is such that colors may be mixed on the palette portion, and at any time these colors may be wiped or cleaned off with a sponge or cloth without danger of the colors or dirt running back into the color-dish or slants.

My invention consists in forming the combined structure in such a shape as to prevent the flow of anything that may be on the palette into the color-dish or slants, and my invention is illustrated in the accompanying drawings, in which—

Figure 1 is a perspective view; and Figs. 2, 3, and 4, modifications thereof, also in perspective.

Similar letters refer to similar parts in the other figures.

The palette part A and color-dishes or slants 3 are integral and separated from each other by the abrupt rib or wall C. The rib may be formed by a part raised above the surface of the palette, as shown in Figs. 1 and 2, or by

a groove D in the surface of the palette, as 35 shown in Figs. 3 and 4. The edge D of this rib forms a barrier and prevents the passage of anything from the palette to the color-dishes, and the edge E may be used for wiping the color from the brush into its proper slant. 40 Any number of color-dishes or slants may be combined with the palette, and in practice the base is cut away to form edges or feet in order more firmly to rest on the table. The whole may be made of any suitable material, 45 such as metal, wood, glass, or porcelain.

Having fully described the nature of my invention, what I claim, and desire to secure by Letters Patent, is—

1. A combined artist's palette and color-dish consisting of a palette connected with one of a series of color-dishes, said palette having a plane, unobstructed, upper surface, and separated from the color-dishes by a rib. 50

2. An article of manufacture consisting of 55 a palette joined to one or a series of color-dishes, said palette having a plane, unobstructed upper surface, and separated from the color-dishes by a rib which is raised above the plane of the upper surface of the dishes, 60 said rib having two edges, one on the palette side and the other on the side of the color-dishes.

ROBERT WILLIAM SEMPLE.
